GAME DEVICE

Robert D. McIntosh, River Forest, Ill., assignor
to The Imperial Brass Manufacturing Company, Chicago, Ill.

Application September 10, 1934, Serial No. 743,389

6 Claims. (Cl. 273—143)

My invention relates to game devices and more particularly to a spinning wheel capable of stopping at a variety of chance combinations of characters.

- 5 The general object of my invention is to provide a device containing rotating discs which stop in certain positions and form, by chance, various combinations of the letters or characters visible thereon.
- 10 Another object of my invention is to provide an exceptionally smooth operating rotating wheel device which lubricates itself from a supply of conserved lubricant during a considerable period of time.
- 15 Another object of my invention is to provide a spinning disc device containing a horseshoe magnetic stopping means which is maintained for an exceptionally long period in a highly magnetized state.
- 20 Still another object of my invention is to supply a revolving wheel apparatus having more than one revolving wheel, in which cushioned friction impellers rotate the axles bearing the wheels, the impellers being of varying sizes and 25 conformation and positioned so that unequal impulses are given to the revolving members by reason of which one will stop before the other.
- A further object of my device is to provide a 30 gaming machine consisting of a pair of rotating metal discs bearing characters which stop in visible positions after the discs are rotated between the poles of a horseshoe magnet, the construction of the moving parts being such that rotation will be prolonged and unequal, the 35 impulse given by rocking a handle attached to frictional cushioned impellers, the device equipped with lubrication reservoirs and of such magnetic construction as to assure a high degree of efficiency over a prolonged period of time.
- 40 In pursuance of the foregoing objects, I aim to provide a small, hand spinning game device in which the characters will stop at definite positions after a smooth long spin. Further objects and advantages of my invention will become apparent as the description proceeds, taken in connection with the drawing which forms part of this specification.

In the drawing:

Fig. 1 is a sectional view showing the mechanism of a preferred form of the device.

Fig. 2 is a top view of the outside of the device showing one of the combinations of characters.

While my invention is susceptible of embodiment in many different forms, I have shown in

the drawing and will herein describe in detail one such embodiment with the understanding that the present disclosure is to be considered as an exemplification of the principles of the invention and is not intended to limit the invention to the embodiment illustrated. The scope of the invention will be pointed out in the appended claims.

When building a gaming device, it is usually the aim to incorporate the psychological elements of expectancy suspense, and sometimes surprise. These features among others often determine the appeal the device will have to the user and must be considered when such a contrivance is designed. Such a machine in order 10 to continue to be popular and in demand must be built mechanically to supply those elements through long periods of use and abuse. In the device presented in this application, the characterized discs come to rest with a final jerk due 20 to strong magnetic attraction after a prolonged spin on well lubricated bearings. The prolonged spin admits of the pleasure of tense expectancy, the unequal spin giving the player an opportunity to read one of the discs while speculating on the stopping position of the next. Among these various slight but significant features are those which spell the difference between a successful machine and a failure, and the unique mechanical accomplishments directed 25 to these ends are the improvements forming the subject matter of this invention.

In the drawing a metal base 1 is attached by screws 2 to a metal trim 3 and a cover 4. Metal discs 5 having the formation of a spoked wheel 35 are rotated by levers 6 by movement of handle 7 acting through rod 8. A horseshoe magnet 9 causes the discs to stop in given positions so that the characters 10 will always appear in clear vision.

The weight and proportion of the device is arranged for permanence and smooth operation. The base 1 is a casting, and the decorative metal trim 2 is clamped between it and the cover, of preferably a lighter resinous compound, by 45 screws 2, of which there may be two, screwed into drilled and tapped bosses 15 in the cover. In the base is also cast or otherwise fastened the horseshoe magnet 9.

The impulse is given to the discs 5 by rocking the handle 7 backward or forward. Handle 7 extends through a slot 16 in the cover 4 and screws into an extension piece 17 which is rigidly attached at 18 to the rod 8. The rod 8 is rotatively mounted on the arms 19 of the base 1.

Inside the arms are collars 20 secured to rod 8 by set screws 21 and bear the levers 6. To the ends of the levers are attached the so termed impellers 25 which are here pictured as resilient cushions which bear frictionally on the bearing shanks 26 and, when moved across them due to the rocking of handle 7, impart a rotating motion to the shanks which in turn rotate the discs 5. The cushions are constructed to compress during contact, and, on snapping back to normal shape, add impetus to the spin of the discs.

Discs 5 are designed for prolonged rotation of different periods. Supporting the bearing shanks 36 of the discs are pins 27 on the outside arms 19 and a pin 28 mounted within on the central arm 19'. Nuts 29 act as lock nuts after pins 27 have been screwed into proper adjustment in tapped holes in arms 19. Bearing cavities 30 are enlarged within to serve as reservoirs for lubricating oil. Discs 5 are mounted on collars 31 which in turn are fastened to shanks 26 to add weight and stability to the rotative parts. The impellers 25 are customarily constructed of different lengths of varied resiliency in order that a single rocking motion of the handle 7 gives unequal impetus to the discs to enable one to come to rest before the other. Apertures 32 in the top 4 form windows for a view of the characters 10 which adorn the several plates 33 of the discs 5.

Long and efficient operation is provided for.

To accomplish this effectively another means is used in addition to the reservoirs for lubricating oil. The horseshoe magnet operable to bring the discs to a stop, as heretofore described has its circuit continuously closed by means of a sectional soft iron bar 36 which is attached to the arm 19 and spans the distance between the poles of the magnet, the strength of the magnet thereby being indefinitely preserved.

In operation the player pushes handle 7 backward or forward. The rocking of 7 produces a simultaneous rocking of the levers 6 which causes the impellers 25 to traverse the circumference of the shanks 26. Discs 5, moved thereby, spin rapidly and on slowing down come to a jerky stop, with some one of the numbers 10 showing, as soon as the force of the spin has abated enough to permit the power of magnet to attract the spoked portions adjacent its opposite poles. Prolonged spin and variety of rotation have been accomplished.

I claim:

1. A game device comprising a base supporting the moving parts and a cover therefor, a pair of characterized ferrous discs of spoke-like construction, individually supported by pin contact bearings mounted on arms extending upward from the base, a rod rotatively mounted on said arms parallel to the points of contact of said bearings, levers rigidly attached to said rod carrying resilient cushion means in traversing contact with said discs and operable, by means of a handle fixed to said rod, to respectively rotate said discs, said cushion means of different lengths and compressibilities to produce unequal rotative impulses on said respective discs, said cushion means of elastic character operable on release to add rotative impulse to said discs, a horseshoe magnet operable by magnetic attraction

on the spoke-like portion whereby the discs stop relatively in some one of a combination of positions, the circuit of said magnet continuously closed by a soft iron bar mounted between its poles, said discs mounted on shafts and having bearing hollows of dimension greater within than at the bearing point to serve as oil reservoirs.

2. A game device comprising a base supporting the moving parts and a cover therefor, a pair of characterized metal discs of spoke-like form, individually supported by pin contact bearings mounted on arms extending upward from the base, a rod rotatively mounted on said arms parallel to the points of contact of said bearings, levers fixed to said rod, in constant relation with said discs carrying resilient cushions operable, by means of a handle rigidly attached to said rod, to respectively rotate said discs, said cushions comprising different compressibilities effective in producing unequal rotative impulses on said respective discs.

3. A game device comprising a base supporting the moving parts and a cover therefor, a pair of characterized metal discs of spoke-like configuration individually supported by pin contact bearings mounted on arms extending upward from the base, a rod rotatively mounted on said arms parallel to the points of contact of said bearings, levers movable with said rod carrying resilient cushion means in contact relation with said discs operable, by means of an attached handle, to respectively rotate said discs, said cushion means constructed of different lengths to produce unequal rotative impulses on the respective discs, a permanent magnet attached to said base adjacent a portion of said discs operable by magnetic attraction on the spokes to cause the discs to stop relatively in some one of a combination of positions, the circuit of said magnet continuously closed by a soft iron bar mounted between its poles.

4. In a game device, indicator disc means rotatable with shaft and bearing means, a plurality of lever arms in traverse contact with the circumference of said respective shaft means, said lever arms having at the point of contact resilient elastic impeller cushions of various predetermined lengths and compressibilities operable to give a correspondingly varied spinning impulse to said shaft means.

5. In a game device a plurality of spoked rotor means mounted respectively on shafts and bearings, a plurality of lever arms in moving contact with said respective shafts, resilient elastic cushion means at each said contact each of a different degree of compressibility operable to effect a correspondingly varied spinning impulse on said rotor means.

6. In a game device, disc means bearing readable characters rotatable on shaft and bearing means, a plurality of lever arms for rotating said disc means in traverse engagement with the circumference of said respective shaft means, said lever means having at said engagement impeller media of different lengths effective to give correspondingly different spinning impulses to said shaft means.

ROBERT D. McINTOSH.
